UNITED STATES PATENT OFFICE.

ALBERT F. FIFIELD, OF NEWARK, NEW JERSEY, ASSIGNOR TO THE SINGER MANUFACTURING COMPANY, A CORPORATION OF NEW JERSEY.

SEWING-MACHINE.

1,226,963.

Specification of Letters Patent. Patented May 22, 1917.

Application filed May 31, 1916. Serial No. 100,804.

To all whom it may concern:

Be it known that I, ALBERT F. FIFIELD, a citizen of the United States, residing at Newark, in the county of Essex and State 5 of New Jersey, have invented certain new and useful Improvements in Sewing-Machines, of which the following is a specification, reference being had therein to the accompanying drawings.

10 This invention relates to sewing machines for producing groups of tacking stitches and more particularly to the work-clamp operating mechanism for single-thread button sewing machines.

15 In button sewing machines it is customary to impart jogging movements to the work-clamp through independent lines of connections which act on the work-clamp in mutually transverse directions and, by actuating said connections simultaneously by means of suitably designed cam-tracks, diagonal jogging movements have commonly been imparted to the work-clamp for the purpose of shifting a four-hole button into 20 positions to receive the well-known diagonally disposed groups of tacking stitches.

25 The patent to J. J. Sullivan, No. 777,564, issued December 18, 1904, discloses a well-known type of lock-stitch button sewing machine having a work-holder actuated in the manner above described. In the Sullivan machine the movements of the work-holder lengthwise of the machine-bed may be suspended by moving a contact-block to the upper end of the lower arm of an actuating 30 rock-lever, where it may be securely held in position coincident with the fulcrum of the rock-lever, the movements of which are thus rendered idle. In this position of adjustment the work-holder will have merely 35 a lateral jogging movement to position the work for reception of a single group of fastening stitches disposed transversely of the machine-bed.

40 In a lock-stitch button-sewing machine such as disclosed in the Sullivan patent it is not particularly important, as far as the stitch-forming operation is concerned, in which direction the work is shifted. In 45 chain-stitch machines, however, it is well-known that as the button and fabric are vibrated laterally of the needle there is a tendency to effect a distortion of the loop of thread drawn out by the looper, whereby

one side of the loop is brought to a position 55 to be caught and broken by the beak of the looper, and such machines are commonly provided with devices for so positioning the distended loop that the needle will descend 60 on the proper side of said loop and present 65 a new loop to be seized by the looper-beak and carried through the previously distended loop.

In single-thread sewing machines having 70 a looper which extends about an axis extending longitudinally of the bed-plate, and fitted with work-holder mechanism such as disclosed in the Sullivan patent it has been found, when the mechanism is adjusted as above described to sew on two-hole buttons, 75 that the jogging movements are imparted to the work in line with the loop-seizing movements of the looper-beak and, as a result, at every alternate stitch the two limbs 80 of the distended loop lie directly in the path of the descending needle and one or the other of said limbs is apt to be caught on the needle-point and broken. The needle is also likely to descend between the limbs 85 of the distended loop instead of descending at one side of said loop as is essential to the formation of enchain loops.

One of the objects of the invention is, therefore, to provide a simplified and improved button sewing machine of the single-thread type which is adapted to sew on two- 90 or four-hole buttons with equal facility.

Another object of the invention is to improve the type of clamp-operating mechanism disclosed in the Sullivan patent so 95 that it may be used in connection with single-thread sewing machines for attaching either two- or four-hole buttons.

Another object of the invention is to provide a train of work-holder operating connections with an improved means for disconnecting it from its actuating means.

A further object of the invention is to provide a fixed stop having a guide which is adapted to coöperate with and determine 100 the path of movement of an element of said disconnecting means when said element is shifted from operative to stationary position.

Other objects of the invention will appear 105 from the following description and appended claims.

In carrying the invention into effect I

- provide work-clamp mechanism, preferably of the type disclosed in the Sullivan patent, with means whereby the connections which impart jogging movements to the clamp laterally of the looper shaft may be rendered ineffective, and I combine such work-clamp mechanism with stitch-forming mechanism preferably of the chain-stitch type such as disclosed in my Patent No. 1,147,386, issued July 20, 1915, in which a looper is mounted on a rotating shaft extending longitudinally of the machine-bed. To arrest the sidewise jogging movements of the work-clamp I prefer to employ a pivoted lever having two parts hinged together. One of these parts is connected to work-clamp and the other carries a cam roll normally disposed within a double walled cam-slot designed to move the lever to-and-fro.
- 20 A manually controlled shaft carrying an eccentric is journaled on one part of the lever and a link embracing said eccentric is connected to the other part of the lever. Partial rotation of the eccentric will withdraw the cam-roll from the actuating cam and force the part of the lever carrying the cam-roll into engagement with a fixed stop which is provided with means acting to shift the lever to a predetermined position, preferably intermediate the extremes of its to-and-fro movement, so that when a two-hole button is placed in the work-holder, the eyes may properly register with the needle.
- 25 In the accompanying drawings, which form a part of this specification, Figure 1 is a side elevation of a button sewing machine embodying my invention. Fig. 2 is a perspective view of the work-clamp and operating mechanism. Fig. 3 is an end elevation of the coöperating stitch-forming elements showing the bed-plate and work-clamp in cross section. Figs. 4 and 5 are plan views, partly in section, of the disconnecting means for the work-clamp mechanism. Fig. 6 is a side view of the disconnecting means. Figs. 7 and 8 are reverse side views of the same in active and disconnected positions, respectively.
- 30 In the preferred embodiment of the invention, as illustrated, the machine frame comprises a base 1 from which rises the hollow standard 2 of the bracket-arm provided with the overhanging tubular portion 3 terminating in the head 4 in which is journaled the reciprocating needle-bar 5 carrying the needle 6 which coöperates with a well-known form of rotating chain-stitch looper having a beak 7 and a loop spreading wing 8. The looper is mounted on a shaft 9 extending longitudinally of an overhanging work-arm 10 which joins the main supporting portion of the frame.
- 35 I prefer to employ the looper operating mechanism, fully disclosed in my said patent No. 1,147,386, in which the looper is given, in addition to its normal loop seizing movements, bodily lateral jogging movements so as to carry the needle-thread loops retained by the looper into engagement with a fixed loop detaining spur 11 on the opposite side of the needle-beak from the loop spreading portion of the looper in its loop-seizing stage of movement, thereby insuring the positioning of the needle-thread loops uniformly for successive stitch-forming cycles regardless of the direction in which the work is shifted.
- 40 The work-clamp is of the well-known form comprising the jogging bar 12 to the forward end of which is secured the fabric supporting plate 13 upon which rests the button-clamp comprising the button gripping jaws 14, 14 carried by the spring-pressed arm 15 secured upon the block 16 mounted on the rearward end of the bar 12.
- 45 To impart longitudinal movements to the work-clamp I preferably employ the usual actuating connections such as shown in the Sullivan patent. These connections comprise the vertical post 17 rigidly sustained by the rearward end of the bar 12 and embraced by a slotted arm 18 of a rock-lever fulcrumed at 19. The other arm 20 of the rock-lever carries a roller 21 which enters a suitable cam-slot in the inner face of the usual cam-wheel 22 actuated, in a manner well-known, by the main-shaft of the machine.
- 50 The adjusting screw 23 is carried by the usual slide block (not shown) which is adapted to be secured in various positions of adjustment on the post 17 to vary the amplitude of the longitudinal jogging movements of the work-holder.
- 55 Acting on the work-holder in a direction transversely of the bar 12 is the well-known train of mechanism comprising the slide-plate 24 secured to the bar 12 by dowel-pins 25 and a screw 26 and carrying the downwardly extending pin 27 connected by link 27' to one arm 28 of a bellcrank-lever fulcrumed on a pin 29 sustained by the work-arm 10. The other arm 30 of the bellcrank-lever is slotted to receive a headed pin 31 connected to one end of an adjustable link 32 whose opposite end is freely connected to the lower end of an actuated member or lever 33 fulcrumed on the transverse pin 34 rigidly held in a socket formed in a bracket 35 bolted to the frame.
- 60 Heretofore, it has been customary to provide the upper end of the lever 33 with a cam roll in permanent engagement with the cam-slot 36 in the outer face of the actuating element or cam-wheel 22 and when sewing on two-hole buttons the adjusting screw 23 was commonly shifted upwardly into alignment with the rock-shaft 19, thereby rendering idle the rocking move-

ments of the slotted lever-arm 18 while permitting the cam-slot 36 to impart lateral jogging movements to the work-holder.

In attempting to sew on two-hole buttons with a chain-stitch machine it is found that when the work is jogged laterally of the looper-shaft, the limbs of the distended loop 37, Fig. 3, lie directly in the path of the descending needle which is apt to catch and break the thread or enter between the limbs of the loops and cause a skipped stitch. To obviate this difficulty, I have arranged to hold the work-clamp in fixed position laterally of the looper-shaft while permitting it to be jogged longitudinally thereof. To this end provision is made for disconnecting the lever 33 from the cam-slot 36 and as a convenient means for accomplishing this result I have formed the lever 33 with a movable follower-element 38 pivoted on a pin 38' secured to the lever 33 and extending transversely of the fulcrum-pin 34. The follower-element 38 is formed with the two cheek pieces 38", engaging opposite sides of the tongue 33" constituting the upper end-portion of the lever 33, and carries a laterally extending pin 39 on which is journaled a roller 40 adapted to enter the cam-slot 36.

Secured to the tongue 33" by a screw 41 is one end of a short link 42 whose opposite enlarged end embraces the eccentric 43 fixed to one end of a shaft 44 journaled in the follower-element 38. A handle 45, secured to the opposite end of the shaft 44, permits the eccentric 43 to be turned to move the roller 40 into or out of engagement with the cam-slot 36. A spring 46 is arranged to press upwardly on the enlarged end of the link 42 to urge the eccentric 43 toward either of the extreme positions to which it may be shifted.

When the lever 33 is disengaged from the cam-slot 36 it is desirable to hold it in fixed position intermediate the extremes of its vibratory movement. For this purpose I preferably mount a vertical guide-pin 41" on top of the hinged follower-element 38 which, when shifted outwardly, carries the pin 41" into the cam-slot 47 formed in the overhanging upper end of a stationary stop-element or bar 48 whose lower end is rigidly secured to the fulcrum-pin 34. Secured to the upper end-portion of the bar 48 by a screw-bolt 55 49 is one end of the bar 50 whose opposite end is apertured to receive the reduced extremity 51 of the rotating shaft which supports the cam-wheel 22. The element 38 together with the pin 41" and the cam-roll 40 may be considered a follower which is acted upon by the cam-slots 36 and 37.

The open end-portion of the cam-slot 47 is in line with the guide-pin 41", as shown in Fig. 4, preferably when the upper end of the lever 33 is at an extremity of its vibra-

tory movement. As the guide-pin 41" is shifted into the cam-slot 47 it strikes the inclined end-portion 52 of said cam-slot and is shifted to the right, Fig. 5, thus moving the lever 33 sufficiently to shift the work-clamp to a position half-way between the extremes of its jogging movement. An adjustable screw 53 and lock-nut 54 are provided to limit the outward movement of the follower-element 38 under the influence of the eccentric 43.

While I have described in detail the preferred embodiment of the invention, it is to be understood that the present improvement is not limited to the details of construction illustrated but may be greatly modified within the scope of the invention which, in certain aspects, is not limited to a chain-stitch machine.

Having thus set forth the nature of the invention, what I claim herein is:

1. A button-sewing machine comprising, in combination, a reciprocating needle, a work-holder, means for producing jogging movements of said work-holder laterally of said needle, said means including an actuating element and a follower normally actuated by said actuating element, a stationary stop, and means for shifting said follower out of engagement with said actuating element and into engagement with said stop.

2. A button-sewing machine, comprising, in combination, a reciprocating needle, a work-holder, means for producing jogging movements of said work-holder laterally of said needle, said means including an actuating element and a follower normally actuated by said actuating element, a stationary stop, and means for shifting said follower out of engagement with said actuating element and into engagement with said stop in a direction transverse to its normal direction of movement as produced by said actuating element.

3. A button-sewing machine comprising, in combination, a reciprocating needle, a work-holder, means for jogging the work-holder, said means comprising independently acting mechanisms operating on the work-holder in mutually transverse directions, one of said mechanisms including an actuating element, a follower normally moved to-and-fro by said actuating element, and means for shifting said follower into or out of engagement with said actuating element.

4. A button-sewing machine comprising, in combination, a reciprocating needle, a work-holder, means for jogging the work-holder, said means comprising independently acting mechanisms operating on the work-holder in mutually transverse directions, one of said mechanisms including an actuating element, a follower normally moved to-and-fro by said actuating element, a stationary stop, and means for shifting said follower

- out of engagement with said actuating element and into engagement with said stop.
5. Work-holder mechanism for sewing machines, comprising, in combination, a work-holder, means for jogging the work-holder, said means comprising independently acting mechanisms operating on the work-holder in mutually transverse directions, one of said mechanisms including an actuating cam, a cam-follower normally moved to-and-fro by said actuating cam, and means for shifting said follower into or out of engagement with said actuating cam.
6. Work-holder mechanism for sewing machines, comprising, in combination, a work-holder, a cam-follower connected to said work-holder, an actuating cam adapted to impart to-and-fro movements to said cam-follower, a stationary stop, and means for shifting said follower out of engagement with said actuating cam and into engagement with said stop.
7. Work-holder mechanism for sewing machines comprising, in combination, a work-holder, a cam-follower connected to said work-holder, a cam adapted to actuate said cam-follower, a stationary stop, and means for shifting said follower out of engagement with said actuating cam and into engagement with said stop, said stop and follower having coacting means adapted to hold said follower in a predetermined position.
8. Work-holder mechanism for sewing machines comprising, in combination, a work-holder, a cam-follower connected to said work-holder, a cam adapted to actuate said cam-follower, a stationary stop, and means for shifting said follower out of engagement with said actuating cam and into engagement with said stop, said stop and follower having coacting surfaces adapted to move said work-holder to a position intermediate the extremes of its operative movements as said follower is shifted to stationary position.
9. Work-holder mechanism for sewing machines comprising, in combination, a work-holder, a cam-follower connected to said work-holder, a cam adapted to actuate said cam-follower, a stationary stop formed with a slot and means for shifting said cam-follower out of engagement with said actuating cam and into engagement with said slot.
10. Work-holder mechanism for sewing machines comprising, in combination, a work-holder, a cam-follower connected to said work-holder, an actuating cam adapted to impart to-and-fro movements to said cam-follower, a stationary stop formed with a cam-slot having an inclined portion, and means for shifting said cam-follower out of engagement with said actuating cam and into engagement with the inclined portion of said cam-slot.
11. Work-holder mechanism for sewing machines comprising, in combination, a work-holder, a cam-follower connected to said work-holder, an actuating cam adapted to impart to-and-fro movements to said cam-follower, a stationary stop formed with a cam-slot having an inclined portion, and an adjustable stop for limiting the movement of said cam-follower when shifted into said inclined portion.
12. Work-holder mechanism for sewing machines comprising, in combination, a work-holder, and independently acting vibratory mechanisms operating on the work-holder in mutually transverse directions, each of said mechanisms including adjustable means for arresting its vibratory motion while permitting continued motion of the other mechanism.
13. Work-holder mechanism for sewing machines comprising, in combination, a work-holder, actuating means therefor, independently acting vibratory mechanisms connecting said work-clamp with said actuating means and operating on the work-holder in mutually transverse directions, adjusting means for rendering one of said mechanisms ineffective, shiftable means for disconnecting another of said mechanisms from its actuating means, and means for holding said last-mentioned mechanism in fixed position when disconnected from its actuating means.
14. A single-thread button sewing machine comprising in combination, a frame, including a bed-plate and an overhanging bracket-arm, a reciprocating needle mounted in said bracket-arm, a rotating looper, a shaft carrying said looper and extending longitudinally of and below said bed-plate, a work-clamp disposed longitudinally of and above said bed-plate, means for imparting simultaneous lateral and longitudinal jogging movements to said work-clamp, whereby crossed diagonal groups of fastening stitches are produced, and means for arresting the lateral movement of said work-clamp, whereby a single group of stitches may be laid in a direction transverse to the plane of rotation of the looper.
15. A button-sewing machine comprising, in combination, a reciprocating needle, a work-holder, means for producing relative lateral jogging movements between said needle and work-holder, said means including an actuating element and a follower normally actuated by said actuating element, a stationary stop, and means for shifting said follower out of engagement with said actuating element and into engagement with said stop.
16. A button-sewing machine comprising,

in combination, stitch-forming mechanism, including a reciprocating needle, a work-holder, means for producing relative lateral jogging movements of said stitch-forming mechanism and work-holder, said means comprising independently acting mechanisms operating in mutually transverse directions, one of said mechanisms including an actuating cam, a cam-follower normally moved to-and-fro by said actuating cam, and 10 means for shifting said follower into or out of engagement with said actuating cam.

In testimony whereof, I have signed my name to this specification.

ALBERT F. FIFIELD.
